UNITED STATES PATENT OFFICE.

ANDREW SANDBERG, OF SEATTLE, WASHINGTON.

LAMP SOCKET.

Application filed August 8, 1927. Serial No. 211,277.

My present invention relates to improvements in lamp sockets of the quick detachable type wherein an incandescent lamp or electric bulb may with facility and convenience be applied to or detached from the socket. In carrying out my invention I utilize a holder within the socket which is designed to receive and retain the stem of the electric lamp or bulb, under frictional engagement between the holder and stem, and gripping arms of resilient metal are employed for receiving and retaining the stem. While the socket and holder are specially designed for use with lamps of this type, it will be understood that other devices, such as wall plugs for electrical connections, may also be used with the lamp socket.

The invention consists in certain novel combinations and arrangements of parts as will hereinafter be more fully set forth and claimed. In the accompanying drawings I have illustrated one complete example of the physical embodiment of my invention wherein the parts are combined and arranged according to the best mode I have thus far devised for the practical application of the principles of my invention.

Figure 1 is a sectional view of the lamp socket showing a portion of a lamp or electric lamp bulb applied thereto.

Figure 2 is a section of the lamp socket at line 2—2 of Fig. 1.

Figure 3 is a perspective view of the lamp holder, detached.

Figure 4 is a sectional view of a wall plug adapted for use with the socket.

In carrying out my invention I utilize the well known type of lamp socket, and for the purpose of illustrating the general assembly and relation of parts I have shown in Figure 1 a portion 1 of an incandescent lamp or electric bulb with a rounded, tapered stem 2 and an annular bead 3 at the end of the stem. The stem and bead of the lamp are designed to co-act with the holder located within the socket which latter is fashioned as usual with the shell 4, open skirt portion 5 and insulated lining 6. The removable cap 7 of the socket carries the hollow plug 8, and the insulated base block 9 is provided with a pair of terminal bolts or screws 10 and 11 passing therethrough. The lead wires 12 and 13 of the lamp circuit pass through the hollow cap-plug 8 and are secured to these terminal posts as usual, and

the two electrodes 14 and 15, fashioned as spring or resilient plates, are anchored to the respective terminals 10 and 11. As shown the electrode 15 is fashioned with a contact plate 16 for co-action with the contact point of the electric lamp, and these parts are normally in contact when the electric bulb is supported within the holder located in the lower portion of the socket. A transversely disposed switch key 17 and its cam 18, the latter located within the hollow base block, are utilized for controlling the lamp, and it will be apparent that the key, when turned at right angles to the positions shown in Figures 1 and 2, will contact with the electrodes 14 and 15 and move them to the dotted line positions of Figure 1. When the key is turned to off position, the cam is released from the resilient electrodes and they return to normal position.

The lamp holder is retained within the lower open end of the socket, through which end the stem of the bulb is inserted as shown in Figure 1.

The holder is fashioned of resilient metal, and as best seen in Figure 3 is provided with a base ring 19 that snugly fits within the lower open end of the socket. The base ring is fashioned with a pair of integral attaching arms 20 and 21 located at diametrically opposite points of the ring and each arm is provided with a perforated attaching lug 22 through which attaching screws 90 are passed for securing the arms to the base block in the socket for the purpose of retaining the holder within the open end of the socket as in Figures 1 and 2.

At two points diametrically opposite the attaching arms, the holder is fashioned with a pair of clamp arms as 23 and 24 that project upwardly into the socket, and these arms are each formed with an arcuate exterior bead that provides an arcuate interior groove, which grooves are adapted to clamp against and support the bead 3 of the lamp when it is desired to hold the lamp in detached position within the socket.

At their free ends both of the clamp arms 105 are formed with compressible hooks 26, and these hooks are fashioned with inner faces 27 that flare outwardly as indicated in the drawings. Thus as the lamp is inserted within the open end of the socket and its holder, the clamp arms 23 and 24 which normally taper inwardly, are spread outwardly

by contact from the bead and stem of the lamp, until the hooks at the ends of the clamp arms are frictionally engaged by the bead. The hooks are thus compressed between the bead and the socket shell and by their frictional engagement with the bead the hooks hold the stem in position. Due to the inclined faces 27 of the hooks and the resiliency of the metal of the hooks the latter tend to pull the stem within the socket and thus hold the contact point of the lamp in contact with the contact spring 16 of the socket.

In Figure 4 a wall socket-plug or connector 28 is shown having a bead 29 that is slipped into the holder, the bead taking the place of the bead 3 of the lamp in Figure 1. The contact point 30 of the plug 28 is thus held in contact with the spring contact arm 16 of the socket. The plug may be substituted for the lamp and used as a connector in the electrical wiring of a circuit. This plug as shown has a slidable head 31 and wires 32, and when used as a wall socket in Figure 4 the slidable head is shoved on the

plug as indicated by dotted lines, to force the blades or electrodes 33, 33, into the wall socket shown by dotted lines at 34.

Having thus fully described my invention, what I claim as new and desire to secure by Letters Patent is—

1. The combination with a lamp socket of a holder comprising a base ring within the socket, attaching arms on said base ring and means for securing the arms to a portion of the socket, clamp arms of resilient metal carried by the base ring, said arms tapering inwardly, and compressible hook members at the free ends of said arms. 35

2. A lamp holder comprising a base ring and a pair of integral attaching arms, a pair of inwardly bent resilient clamp arms each having a transverse bead to form a pair of clamp grooves, and compressible hooks having inclined faces formed at the free ends of said clamp arms. 40 45

In testimony whereof I affix my signature.

ANDREW SANDBERG.
